UNITED STATES PATENT OFFICE.

WILLIAM A. FULLER, OF ROCK ISLAND, ILLINOIS.

ELECTRIC HEATER.

SPECIFICATION forming part of Letters Patent No. 731,768, dated June 23, 1903.

Application filed March 26, 1903. Serial No. 149,707. (No model.)

To all whom it may concern:

Be it known that I, WILLIAM A. FULLER, a citizen of the United States, residing at Rock Island, in the county of Rock Island, State of Illinois, have invented certain new and useful Improvements in Electric Heaters, of which the following is a specification.

The object of my present invention is the production of an electric heater which is compact and durable and which possesses other advantages of construction, arrangement, and operation over those heretofore known.

My invention consists in certain features of novelty, which will be pointed out in the claims hereto annexed as a part of this specification.

For a better understanding of my invention reference may be had to the accompanying drawings, of which—

Figure 1 is a plan view. Fig. 2 is an elevation, partly broken away; Fig. 3, a perspective view illustrating details of construction. Fig. 4 is a diagram illustrating the various circuits; and Figs. 5 to 9, inclusive, are diagrams showing various ways in which the heating-conductors may be connected.

The casing or framework of the heater may be formed of cast metal and is substantially box-like in form. The front of the casing in the construction which I have illustrated in the drawings consists of two plates or members 1, connected together by screws 2. To these front pieces are secured two end plates or members 3. The front members 1 may be formed with flanges 4, to which the end members 3 are connected by screws 5. A side member 6, curved as shown in Fig. 1, closes one side of the box-like casing. It is provided with end flanges 7, similar to the flanges 4 of the members 1, and is connected to the end members 3 by screws 8. As shown in Fig. 2, the side piece 6 extends the entire distance between the ends 3 of the casing. The opposite side of the frame may be closed by a similar piece 6, if desired, or it may be left in the form shown in the drawings, in which case the heater may be enlarged, if desired, by adding to it other sections or portions similar in general to the one shown. The

front members 1, ends 3, and side member 6 are perforated, as clearly shown in the drawings. Perforated lugs 9, extending from the end pieces 3 and the side piece 6, form a means by which the heater may be secured against a wall or other place of support. The back of the casing may be closed or not, depending upon the locality in which the heater is employed.

Stove-bolts 10, passing through the end pieces 3 and the bottoms of the trough-shaped supports 11, are provided with nuts on their inner ends and position the supports 11. These supports are arranged in pairs, the opposite members of each pair being secured to opposite end plates 3. The trough-shaped supports 11 are formed of sheet-brass or the like and open toward one another, as is clearly shown in Fig. 3. A pair of strips 12, of sheet-brass or the like, extend between each pair of supports 11 and are secured by rivets or the like to the ends and at the rear of these supports, as clearly shown in Fig. 3. A similar pair of supports 13 extend between opposite supports and are secured at the ends of the supports on their front sides, as is clearly shown in the drawings.

Each pair of supports 11 and the corresponding strips 12 and 13 form a skeleton frame or cage 13', which is supported between the end members 3 by the bolts 10. The strips 12 and 13 may be connected intermediate of their ends by a support or stay, if desired, as indicated at 13' in Fig. 2. If the strips 12 and 13 be made somewhat shorter than the distance between the end plates 3, the expansion of the frame 13', due to an increase in temperature, will not have a tendency to distort the frame or casing, owing to the play which may take place between the ends 3 and the supports 11, the bolts 10 readily permitting this play. Strips of asbestos or similar material 14, which may be channel-shaped, as shown in Fig. 3, embrace the sides of the skeleton frame 13'.

Resistance-wires formed into helices in any suitable manner, as by winding over a mandrel, are wound one each around each of the box-like skeleton frames 13' in the form of

helices 14', having rectangular coils, as is clearly shown in that portion of Fig. 2 in which the plate 1 is broken away. In this connection it will of course be understood that in the actual heater the coiled resistance-wires are seen through all the interstices of the casing; but in order to avoid confusion in the drawings I have shown the helix only where the casing is broken away. The ends of the resistance-coils are secured to insulators 16, secured to the framework of the coil-supports, as shown in Fig. 3. Supports of insulating material similar to the insulators 16 may be placed at intervals along the strips 12 and 13, if desired, in order to maintain the coils in position. As is well known, however, a helix wound in the manner described has a tendency to increase its grip upon the support when it expands upon a temperature increase.

The particular heater which I have illustrated in the drawings is intended to be operated upon a three-phase alternating-current-supply system. In the diagram shown in Fig. 4 the three helices 14' are shown as being connected one each through switches 15, 16, and 17 to lines 15', 16', and 17', extending from the three-phase supply-lines 18 19 20. The other ends of the coils 14' are connected to switches 21, 22, and 23, pivoted at 21', 22', and 23', respectively. The switches 21, 22, and 23 are connected to a bar 24, having a handle 25, by means of which the switches may be simultaneously operated. When the switches 21, 22, and 23 are in the position shown by full lines in Fig. 4, the coils 14' are connected at one side by means of a short-circuit connection 26. When the switches 21, 22, and 23 are in the position shown in dotted lines in Fig. 4, the coils are connected to the lines 16', 17', and 15', respectively.

The various arrangements of the circuits in the heater and corresponding variations in the amount of energy consumed and heat produced by manipulations of the switches 15, 16, 17, 21, 22, and 23 are illustrated in Figs. 5 to 9, inclusive. In Fig. 5 the switches 21, 22, and 23 are in the dotted-line position and the switches 15, 16, and 17 are all closed. In this case the three heating-coils are all in use, being arranged in delta. In the arrangement shown in Fig. 6 the switches 21, 22, and 23 are also in the dotted-line position and the switches 16 and 17 are closed. The switch 15, however, is open. In this arrangement two of the heating-coils are in operation and the energy consumed is two-thirds of that when the circuits are arranged as shown in Fig. 5. In the arrangement shown in Fig. 7 the switches 15, 16, and 17 are closed, and the switches 21, 22, and 23 are in the full-line position. In this arrangement all of the coils are in operation, but are connected in the star relation. In the diagram illustrated in Fig. 8 the switches 21, 22, and 23 are in the

dotted-line position and the switch 17 is closed. The switches 15 and 16 are open, however, so that only one coil is in operation. In the arrangement shown in Fig. 9 the switches 21, 22, and 23 are in the full-line position and the switches 16 and 17 are closed, the switch 15 being open. This results in placing two of the heating-coils in series between two of the supply-lines. It is seen, therefore, that the arrangement of switches described gives a very wide variation in the heating effect upon simple manipulations of the switches. In practice it will of course be understood that the switch 21 may be the standard form of three-blade double-throw pivoted switch or any other of the ordinary forms of switches instead of that shown. The rectangular form of the coil-supports and the coil wound thereon makes a very compact arrangement. The construction of the coil-support out of sheet metal is especially advantageous, owing to its cheapness and to the mechanical strength which can be obtained with a minimum amount of material.

The skeleton construction of the coil-supports permits a very efficient air circulation through the heaters.

What I claim as new, and desire to secure by Letters Patent of the United States, is—

1. In combination, a plurality of bars arranged to form an open box-like structure, and a helical conductor wound in a helix around said bars. 95
2. In an electric heater, a resistance-conductor formed into a helix, the helical conductor in turn being formed into a helix the coils of which are substantially rectangular. 100
3. In combination, a casing, groups of metallic bars extending from opposite sides of said casing, the bars in each group being arranged to form an open substantially rectangular casing, a helical conductor wound in a helix about said bars, and means for insulating said conductor from said bars. 105
4. In combination, a plurality of metal bars secured together to form a rectangular cage, and a helical resistance-conductor wound about said bars. 110
5. In combination, a plurality of strips of sheet metal arranged to form a cage having a substantially rectangular section, and a helical resistance-conductor wound in a helix about said cage, the coils of said helix being substantially rectangular. 115
6. In combination, a pair of supports, a skeleton frame formed of sheet metal held between said supports by means allowing the frame to expand, and a resistance-conductor wound on said frame. 120
7. In an electric heater, a coil-support substantially rectangular in cross-section, insulation embracing opposite sides of said support, and a conductor wound about said support. 125
8. In an electric heater, a metallic support. 130

ing-casing having a box-like form, a plurality of coil-supports lying side by side in said casing, the coil-supports being substantially rectangular in cross-section, and conductors wound about said coil-supports.

9. In combination with an electric heater having three resistance-conductors, a three-phase current-supply system, and means for connecting the conductors in the delta rela-

tion or in the star relation to said supply system.

In witness whereof I have hereunto set my hand this 21st day of March, 1903.

WILLIAM A. FULLER.
